ATTENUATOR

Arnold J. Hyatt, Richmond Hill, N. Y., assignor
to A. F. Smuckler & Co., Inc., Brooklyn, N. Y.,
a corporation of New York

Application December 2, 1949, Serial No. 130,791

1 Claim. (Cl. 178—44)

1

The present invention relates generally to a radio frequency step attenuator and is more particularly directed to an apparatus of this type which may be employed for ultra high frequency waves or microwaves. In order that the attenuator may be useful in these ranges the conductors or resistances employed are of the coaxial type. It is one of the objects of the present invention, therefore, to provide an attenuator of simple and rugged construction and which employs the axial type of resistors.

Another object of the invention is to provide a completely shielded attenuator of the type described.

A still further object of the invention is to provide a variable attenuator having a range of 30 decibels operable in four equal steps.

Another object of the invention is to provide an attenuator of the type described in which the error of deviation to frequency characteristics shall be less than 10% throughout the frequency range of 70 kilocycles to 600 megacycles.

Another still further object is to provide an attenuator which may carry a load or receive an input consisting of 100 volt pulses with a 0.125% duty cycle.

A still further object of the present invention is to provide an attenuator of the class described in which the effects of temperature, humidity, and voltage on its accuracy is minimized.

For the purpose of a fuller and more detailed description of the present invention and of its many objects and inventions, reference is had to the accompanying drawings and the following specification which illustrate one specific embodiment of the present invention; it being understood that variations thereof falling within the scope of the appended claim will be apparent to persons skilled in the art.

In the drawings:

Fig. 1 is a front end view of the attenuator.

Fig. 2 is a longitudinal sectional view on line 2—2 of Fig. 1.

Fig. 3 is a transverse sectional view on line 3—3 of Fig. 2.

Figs. 4, 5, 6, 7, and 8 are partial longitudinal views on each of the resistor circuits respectively.

Fig. 9 is a detail sectional view.

In its broad outlines the present attenuator consists essentially of a metal housing and a turret disposed within the housing. The turret, preferably a solid cylindrical metal body, is provided with an outer and an inner series of circularly disposed passages or barrels extending from end to end. Each pair of passages or barrels,

2

one from the outer and one from the inner series, disposed radially with reference to each other, are connected to each other by a recess in one end of the turret. Thus the pair of barrels with the recess form a U-shaped conduit for the reception of conductor-resistors of the coaxial type. The free ends of the barrels carry connectors of the coaxial type for separably connecting with a co-operating pair of fixed connectors carried by an end plate of the housing or casing. In its normal position the turret is maintained against accidental rotation and a selected pair of coaxial conductor-resistors are in engagement with the fixed connectors on the casing and the cables attached thereto may, therefore, receive the load or input and pass the same through the desired or connected pair of attenuating conductors or resistors. When it is desired to change the attenuation, the turret is first moved axially to disengage the turret from the fixed connectors on the end plate of the casing and the turret is then rotated into the desired position for the engagement of another pair of attenuating resistances with the fixed connectors on the end plate of the casing or housing.

With the above outline of the broad aspects of the construction of the present attenuator, a more detailed description of the several elements will now give a full understanding of the invention.

30 The metal housing or casing comprises a tube or cylinder 10, a front end plate 11, and a rear end plate 12. The end plates have lower straight edges and are otherwise shaped as shown in Figs. 1 and 3, and have attached thereto feet or brackets 13. The inner faces of the front and rear plates are each provided with an annular shoulder 14 to receive the tube 10. Tie rods 15 connect the marginal portions of the end plates 11 and 12 and the assembly is held firmly secured by the cap nuts 16. The detent 17 is mounted on the outer face of the tube or cylinder 10 and its detent lug 18 and extends interiorly of the tube for engagement with one of the grooves 19 in the turret 20 to prevent its accidental rotation as shown in Figs. 2 and 3.

40 The turret 20 is a cylindrical body of metal, such as brass or the like, which may be provided with the circular series of passages 21 to reduce its weight. One end of the shaft 22 is lodged in the bearing 23 carried by the rear plate 12 and the other end of the shaft 22 passes through a corresponding opening in the end plate 11 and carries the handle 24 which is provided with a pointer 25. The exposed face of the end plate

11 is provided with several indicia as shown in Fig. 1 to indicate the step positions of the shaft and also to indicate the degree of attenuation in each of these positions. The turret 20 is held firmly secured to the shaft 22 by the set screw 26. The forward end of the turret is provided with a recess 27 which receives the helical spring 28 interposed between the bottom of the recess and the inner face of the end plate 11, thereby holding the turret and its shaft in the normal or engaged position shown in Fig. 2. Spring retainers 29 are disposed at the ends of the spring 28.

The outer cylindrical face of the turret 20 is provided with a circular channel 30 designed to receive the upper end of the detent 18 to permit rotation of the turret 20. Relatively short longitudinal grooves 19 branch out from channel 30 and serve to receive the detent 18 when the turret is in an engaged position. When it is desired to switch or change the position of the turret, it is moved axially against the spring 28 until the detent 18 enters the channel or passage 30. The turret may then be rotated to desired position and when released the spring 28 will move it to the position shown, while it is being guided by the detent 18 and the corresponding passage or groove 19.

The front end of the turret is provided with a series of radial recesses 31 substantially oval in shape as shown in Fig. 3. A pair of longitudinal open-ended bores or barrels 32 extend the entire length of the turret from the end of each recess 31. Each bore or barrel 32 has an enlarged portion 33 at its rear end which receives the coaxial type of separable connector 34. The shoulder 35, against which the connector 34 abuts, preferably extends somewhat into the passage or bore 32.

The bores or barrels 32 receive coaxial conductors or coaxial type attenuating resistors and the recess 31 receives the coaxial jumper conductor 36 for connecting the two longitudinal coaxial conductors or resistors. Thus each pair of parallel and radially spaced longitudinal barrels, together with its associated recess 31, form a U-shaped passage or conduit for housing coaxial attenuator conductor-resistors.

All of the jumper conductors 36 are of the same construction. They each comprise a short length of insulation filled coaxial cable 37 which join a pair of short metal cylinders 38 disposed in the forward end of each barrel or bore 32. The central conductor 39 in the jumpers extends at each end into the cylinders 38 and the ends are bent downwardly as shown in dotted lines in Fig. 4 and enter suitable recesses in the ends of the conductor-resistors disposed in the passages 32.

The conductors or the resistors disposed in the barrels 32 of the turret vary for the purpose of varying the degree of attenuation. Thus in one pair of barrels, which may be spoken of as the zero pair, illustrated in Fig. 4, there are no resistors and these contain the coaxial conductors consisting of the coaxial conducting sleeve 40 and the coaxial conductor 41. The sleeve 40 abuts the shoulder 35 and the insulating spacer disk 42 at the other end. The conductor 41 at one end enters a recess in the central electrode 43 of the quick detachable connector 33. At its other end the conductor 41 has a reduced portion that passes through the spacer disk 42 and receives the bent end of the conductor 39.

Thus in the position of zero attenuation the two barrels each carry substantially non-resistive coaxial cables in series with the coaxial jumper

that unites the two barrels and when the turret is in this position as shown in Fig. 2, the power coming in by one of the cables 44 leaves by the other substantially unattenuated.

The second pair of passages or barrels 32 that correspond to the 20 decibel position, one carries a coaxial conductor 40, 41, which is the same as in the zero position. In the other passage of this pair, as will be seen in Fig. 5, a rod and disk resistor unit is inserted in series with the coaxial conductor. The rod 45 is of ceramic material or other suitable insulating material with a thin coating of resistive conducting material and capped by conducting caps 46, each having a projecting wire 47. At one end the wire 47 enters a suitable recess in the end of the conductor 41. At the other end, the wire 47 enters the passage of the retainer 48 which is interposed between the rod and the disk 49. The disk is made of Bakelite or any other suitable material coated with a thin resistive coating of conductive material. The retainer 48 has a shoulder which abuts the disk and a reduced portion that passes through an opening in the disk and joins with the conductor 43 of the quick detachable connector 33. In this position the degree of attenuation is ten, the signal being reduced by the rod and disk unit to one tenth of its original strength.

In position 3 or in the 40 decibel position, as shown in Fig. 6, two rod and disk units are employed in series as shown. In this the degree of attenuation is one hundred, the signal being reduced to one hundredth its original strength.

In the fourth or 60 decibel position, as shown in Fig. 7, two rod and disk assemblies are employed in series in one leg of the conductor resistor and a third rod and disk assembly is mounted in the other leg. In position 5 or in the 80 decibel position, two such assemblies are disposed in each leg of the resistor, as shown in Fig. 8. In these positions the degree of attenuation is 1,000 and 10,000 respectively.

The manner in which the resistor disk 49 is held in position between a pair of rods 45 is illustrated in Fig. 9. The retainer 48 is provided with an axial passage receiving the wires 47 from the adjacent rods. The reduced portion of the metallic retainer passes through the central aperture in the disk 49 and receives the metallic annulus 51 which bears against the other face of the disk. Thus the disk is held between the elements 48 and 51 and the latter are held between the adjacent rods 45. The rod resistor element 45 is a ceramic rod coated with a thin layer of carbon originally applied in the form of a carbon paint or a carbon suspension. The shunt elements, the apertured disks 49, are preferably made of a plastic, such as Bakelite or the like, and are similarly coated with a thin layer of carbon. These attenuator elements have a constant resistance, a phase angle of 0, and a power factor of unity. These resistors do not possess any magnetic field nor an electric field and self-inductance and self-capacitance are reduced to a minimum. The rod resistors are very small in cross section, and in the present embodiment of the invention they are less than $1/8$ inch in diameter, thereby substantially eliminating the skin effect, and the ceramic insulating material employed is of very low power loss thereby preventing the increase of its conductance with a rise in frequency.

The rod resistor 45 employed in the present embodiment of the invention has a resistance of 450 ohms, and maintains an essentially resistive

characteristic up to and including 600 megacycles and throughout the range of the attenuator. When the resistance of the rod unit is increased, capacitance effects enter at the higher frequencies as the frequencies approach 600 megacycles. Thus the present apparatus employs the single rod in the 20 decibel attenuation and employs 2 or 3 or 4 such rods in series in the higher attenuations. If, instead of employing several rod and disk units, a single rod and disk unit having a much higher resistance were employed, the conditions of 0 phase angle and unity power factor would not exist.

The input shunt disk elements 49 each have a resistance of 55 ohms and the output shunt disk elements 50 each have a resistance of 50 ohms. Broadly described the present attenuation system employs a T network in which the resistance units in the inner conductor are each 450 ohms of the type described herein and the shunt units are the disks which are 55 or 50 ohms as described, there being at least one such shunt disk associated with each rod or at least one such shunt disk between adjacent rods.

I claim:

A shielded attenuator comprising a metal hous-

ing, a metal turret disposed within the housing, the turret having a series of parallel passages, co-axial resistor conductors disposed in said passages, co-axial conductors mounted on one end of said turret and connecting adjacent resistor conductors in pairs, a connector carried by the other end of each resistor, a pair of fixed connectors carried by the housing for separable and selective connection with any desired pair of said first mentioned connectors, and means for moving said turret into selective engagement between said pair of fixed connectors and a selected pair of resistor connectors.
